United States Patent Office

Des. 198,722
Patented July 21, 1964

198,722

WASTE BASKET

Frank W. Cooper, Pittsburgh, Pa., assignor to Federal Enameling & Stamping Company, Pittsburgh, Pa., a corporation of Michigan

Filed July 24, 1963, Ser. No. 75,950

Term of patent 14 years

(Cl. D58—17)

Fig. 4

Fig. 5

Fig. 6

Fig. 7

FIG. 1 is a perspective view of a waste basket showing my new design.

FIG. 2 is a fragmentary sectional view thereof taken along the line 2-2 of FIG. 1.

FIG. 3 is a fragmentary sectional view taken along the line 3-3 of FIG. 1.

FIG. 4 is a top plan view of the waste basket shown in FIG. 1, with the open work omitted from certain of the basket sections, for convenience of illustration.

FIG. 5 is an enlarged fragmentary sectional view of a portion of the wall shown in FIG. 3.

FIG. 6 is a fragmentary sectional view along the line 6-6 of FIG. 4.

FIG. 7 is a fragmentary sectional view along the line 7-7 of FIG. 5.

I claim:

The ornamental design for a waste basket, as shown and described.
